Primary Examiner — John Windmuller(57) **CLAIM**

The ornamental design for a watch winder, as shown and described.

DESCRIPTION

FIG. 1 is a front elevational view of a watch winder showing my new design;

FIG. 2 is a rear elevational view thereof;

FIG. 3 is a left side view thereof at an enlarged scale;

FIG. 4 is a right side view thereof at an enlarged scale;

FIG. 5 is a top plan view thereof;

FIG. 6 is a bottom plan view thereof;

FIG. 7 is a perspective view thereof; and,

FIG. 8 is a perspective view thereof with the cover opened. The broken lines in FIG. 6 depict portions of the watch winder that form no part of the claimed design.
